(57) **CLAIM**

The ornamental design for a disposable lid for a container, as shown and described.

DESCRIPTION

FIG. 1 is a top perspective view of a first embodiment of a disposable lid for a container showing my new design in a closed position;

FIG. 2 is a bottom perspective view thereof;

FIG. 3 is a top plan view thereof;

FIG. 4 is a front elevation view thereof;

FIG. 5 is a rear elevation view thereof;

FIG. 6 is one side elevation view thereof;

FIG. 7 is another side elevation view thereof;

FIG. 8 is a bottom plan view thereof;

FIG. 9 is a top perspective view of the disposable lid for a container of FIG. 1 shown in an open position;

FIG. 10 is a bottom perspective view thereof;

FIG. 11 is a top plan view thereof;

FIG. 12 is a front elevation view thereof;

FIG. 13 is a rear elevation view thereof;

FIG. 14 is one side elevation view thereof;

FIG. 15 is another side elevation view thereof;

FIG. 16 is a bottom plan view thereof;

FIG. 17 is a top plan view of a second embodiment of the disposable lid for a container showing my new design in a closed position;

FIG. 18 is a front elevation view thereof;

FIG. 19 is a rear elevation view thereof;

FIG. 20 is one side elevation view thereof;

FIG. 21 is another side elevation view thereof;

FIG. 22 is a bottom plan view thereof;

FIG. 23 is a cross-section view according to section line 23-23 of FIGS. 3 and 17; and,

FIG. 24 is a cross-section view according to section line 24-24 of FIG. 11.
